INVENTOR

August J. Kloneck.

UNITED STATES PATENT OFFICE.

AUGUST J. KLONECK, OF NEW YORK, N. Y.

SIGNALING DEVICE.

1,223,589.

Specification of Letters Patent.

Patented Apr. 24, 1917.

Application filed January 28, 1914. Serial No. 814,989.

To all whom it may concern:

Be it known that I, AUGUST J. KLONECK, a citizen of the German Empire, having declared my intention to become a citizen of the United States and received my first citizen papers, residing at New York, in the county of New York and State of New York, have invented new and useful Improvements in Signaling Devices, of which 10 the following is a specification.

This invention relates to signaling devices and its object is to produce high frequency electrical oscillations with greater efficiency than those hitherto in use.

15 A further object is to provide an apparatus and an arrangement of electric circuits for generating high frequency currents, whereby a weak electric current induces powerful high frequency oscillations.

20 Another object is to provide the apparatus with an arrangement of electric circuits for amplifying electric currents.

The invention consists of certain novel features of electric circuits and combinations 25 of parts hereinafter described and more particularly pointed out in the claims.

In the accompanying drawings are shown several arrangements of electric circuits and apparatus; but it will be understood that I 30 do not limit myself to the arrangements set forth, but consider myself at liberty to make such changes and alterations as may fall within the scope of the appended claims.

In the drawings, in which similar numerals 35 designate similar parts; Figure 1 illustrates my apparatus with one form of electric circuits for generating high frequency currents, Fig. 2 illustrates the apparatus with a modified arrangement of electric circuits. Fig. 3 40 illustrates the apparatus with another modified arrangement of electric circuits, of which the inducing current of the transmitter excites the field magnet of the electric generator and thereby changes the current 5 flux through the oscillator.

By reference to the drawings, 1 represents an incandescent lamp with an enlarged bulb, 2 represents a tube of a suitable metal, provided to be heated and penetrable for gas in 0 the heated condition, serving to change the contents of the bulb. 3 and 4 are suitable electrodes of metal plates or wires conveniently arranged within the bulb, having a conductor to the exterior, 5 is the blow out 5 coil, provided within or beyond the bulb. The coil 5 sets up a magnetic field perpen-

dicularly on the radiating current and blows out the radiations of the current between the electrodes, by means of the magnetic force, induced through the coil, 6 denote batteries 60 or other generators of electric currents, 7 represents large electric generators such as dynamos, the numeral 8 denotes means for varying electrical currents, which may be microphones, the numeral 9 represents the 65 primary of an oscillation transformer.

The operation of the oscillator is similar to that of the arc type, except that instead of the arc, the less luminous radiation of a larger area of electrodes is used, and the radiation of the current is occasioned by a glowing filament in the bulb.

A direct current generator 7 has its terminals connected to the electrodes 3 and 4. When the filament becomes heated by a battery 6 the resultant electronic radiation from the heated filament breaks down the resistance within the bulb between electrodes 3 and 4, permitting current to flow in the nature of an arc from one electrode to the other. Included in the circuit of electrodes 3 and 4 and generator 7 is the coil 5, which when the arc current begins to flow sets up a magnetic field within the bulb in a direction perpendicular to the arc itself. This 75 blows out the arc and the cycle is repeated, thus setting up a high frequency current. The electromagnetic field, due to coil 5, may take a short time to build up after the arc between electrodes 3 and 4 has begun and 80 when the coil 9 of the oscillation transformer is connected in shunt to the oscillator as in Fig. 1, the current to the transformer is diminished through the radiation of current between the electrodes, while 85 when the transformer 9 is connected in series with the coil 5, the generator 7 and the electrode, as shown in Fig. 3, radiation causes the coil 9 of the transformer to be 90 energized.

100 It will be obvious that the apparatus will amplify currents of any device whether that of a transmitter or of a receiving apparatus. Such instrument can be included in the circuit in different manners, and in the drawings only such connections are illustrated, as permit the use of an ordinary transmitter 8 and a source of a small electrical current to vary a powerful sending current. In Fig. 1 the transmitter is connected in series with 110 the battery 6^b and the blow out coil 5. The increase of current through the transmit-

ter energizes the blow out coil 5 and decreases the radiation of the main current, or the transmitter 8 may be connected in series with the filament, the battery 6 and a resistance 13, causing radiation of the main current, as Fig. 2 illustrates. Fig. 3 illustrates the transmitter in series with the small generator 7^b and field coil 7^c of the main generator 7. The transmitter varies the magnetism in the field magnet of the main generator, thus varying currents in the armature of the generator 7.

The secondary of the transformer 9 may be connected with the antenna for sending radio signals, or to other apparatus, as convenient or desired.

It will be obvious that a metallic tube 2, if heated electrically or otherwise, permits an exhaustion and refilling of the bulb with any convenient gases, inasmuch as heated metals are penetrable for gases, thus the sensitiveness and life of the device may be increased to a considerable time.

Having now described my invention what I claim as new and desire to secure by Letters Patent is:

1. A signaling device, consisting of a receptacle having inclosed therein two arcing electrodes, incandescent means and a blow out coil.

2. A signaling device, consisting of a receptacle having inclosed therein a plurality of arcing electrodes and incandescent means, one of said electrodes being a blow out coil, said coil being adapted to produce a magnetic field within said receptacle.

3. A signaling device, consisting of a receptacle having inclosed therein a plurality of arcing electrodes and incandescent means, one of said electrodes being a blow out coil, said coil being arranged between the incan-

descent means and another electrode and adapted to produce a magnetic field between the latter.

4. A signaling device, consisting of a receptacle having inclosed therein a plurality of arcing electrodes and incandescent means, one of said electrodes being a blow out coil, said coil being supported at both ends by said receptacle and adapted to produce a magnetic field between said electrodes.

5. A signaling device, consisting of a receptacle having inclosed therein a plurality of arcing electrodes and incandescent means, and a blow out coil, one end of said coil being in connection with another electrode.

6. A signaling device, consisting of a receptacle having inclosed therein a plurality of arcing electrodes and incandescent means, and means for regenerating said receptacle.

7. A signaling device, comprising a receptacle and a blow out coil, a plurality of arcing electrodes inclosed within said receptacle and an incandescent means, said blow out coil being adapted to produce a magnetic field within said receptacle by a discharge of current between said electrodes.

8. The combination with a receptacle having inclosed therein three arcing electrodes and incandescent means, of two separate electric circuits, one for said incandescent means and other circuits embracing said arcing electrodes, said arcing electrodes and said incandescent means having no electrical connection with one another.

In witness whereof I hereunto subscribe my name.

AUGUST J. KLONECK.
